UNITED STATES PATENT OFFICE.

FREDERICK WILLIAM VICKERY, OF LONDON, ENGLAND, ASSIGNEE TO VICKERY'S
PATENTS LIMITED, OF LONDON, ENGLAND.

PAPER-CUTTING MACHINE.

1,109,489.

Specification of Letters Patent. Patented Sept. 1, 1914.

Application filed June 12, 1913. Serial No. 773,827.

To all whom it may concern:

Be it known that I, FREDERICK WILLIAM VICKERY, a subject of the King of Great Britain, residing at London, England, have 5 invented certain new and useful Improvements in Paper-Cutting Machines, of which the following is a specification.

This invention relates to that class of paper cutting machine in which a fixed knife and a rotating knife are employed for cutting sheets of paper from a web by severing the web across its length, and particularly to that class of machines employed for cutting off labels or the like in which fingers 10 are carried around with the rotary-knife, and rocked by cam action to guide and press down the cut labels into a receptacle substantially along their whole length.

Now the object of my invention is to construct the mechanism for pressing down the cut labels so that it can also be employed with ordinary paper cutting machines in which a rotating knife acts against a fixed knife positioned horizontally. Such mechanism operates only upon the leave or tail edge of the cut sheet of paper so as to clear it from the rotating knife edge when the knife is traveling quicker than the paper thus obviating any damage to the cut sheets 20 or blockage in the machine, and also avoiding the necessity for running the usual conveyors in ordinary paper cutting machines at different speeds for every length of sheet cut or in other words having to run the conveyors at the speed of the revolving knife, which of course changes relation to the web of paper according to the size of sheet being cut.

For the purpose of my invention and as 25 shown on the annexed drawing the drum 3, which carries the rotating knife 2, is provided with lugs 12, one on each end and to such lugs is pivoted a rod 10, said rod carrying arms 11 having attached at their front 30 ends a strip 5 extending across the machine and positioned in front of the rotating knife 2. Projecting on the other side of the rod 10 is an arm 9 having a roller 8 at its free end which rides against a cam face 6 35 fitted in the frame 7 of the machine. The arms 9 and 11 are fixed to the rod 10 so that they rock about the same and one of the arms 11 is provided with a spring 13 which normally presses against the drum 3 to keep

the strip 5 just under the knife 2 and inside 55 the radius of the travel of its cutting edge.

The fixed knife 1 is positioned approximately horizontally and in the horizontal line of the shaft 14 carrying the drum 3 and the paper is fed over the edge of the knife 1 down the board 15 on to the traveling tapes 4 which run in the same line as the feed of the paper.

In action the arms 9, 11, and spring 13 revolve with the drum 3 and knife 2, the strip 5 being disposed just under the knife 2 and within the radius of movement of its cutting edge but just as the knife 2 has passed over the knife 1 and severed the paper the roller 8 rides against the cam face 6 and thus projects the strip 5 which acting upon the tail or leave end of the cut sheet only pushes such leave or tail end over out of the path of the travel of the knife 2 so that during the continued travel of such knife 2 the cut sheet will not be struck by it and so soon as the roller 8 leaves the cam face 6 the spring 13 returns the strip 5 to its former position under the knife 2. During the revolution of the drum 3, the paper has 60 been passed on to or nearly on to the traveling tapes 4 and so soon as the cutting takes place the leave or tail end or edge is pushed over on to the board 15 and the sheet is carried away by the tapes 4. It will thus 65 be seen that the strip 5 can only act upon the tail or leave end of the cut sheet so as to pass such end out of the path of travel of the rotating knife, and that it only acts on the sheet when the revolving knife is 70 traveling faster than the paper.

What I do claim as my invention and desire to secure by Letters Patent is:—

1. In a paper cutting machine, the combination, with coacting fixed and rotary knives; of means engageable with the rear end of a cut sheet for moving said end out of the path of the rotary knife, to permit the latter to clear said sheet.

2. In a paper cutting machine, the combination, with coacting fixed and rotary knives; of means connected with the rotary knife for movement therewith into engagement with the rear end of a cut sheet for moving said end out of the path of the rotary knife, to permit the latter to clear said sheet.

3. In a paper cutting machine, the combi-

nation, with a fixed knife, a rotary drum, and a knife carried by said drum for coaction with the fixed knife; of a device connected with said drum, and located in advance of and beneath the second-named knife; and means for moving said device into engagement with the rear end of a cut sheet, to shift said end out of the path of said second-named knife to permit the latter to clear said sheet.

4. In a paper cutting machine, the combination, with a fixed knife, a rotary knife-carrier, and a knife mounted on said carrier for coaction with the fixed knife; of a spring-controlled member connected with said carrier and normally located beneath and within the path of the second-named knife; and means for periodically moving said member out of said path into engage-

ment with a cut sheet, to permit said second-named knife to clear said sheet.

5. In a paper cutting machine, the combination, with coacting fixed and rotary knives; of a member yieldingly connected with the rotary knife and located in advance of and beneath the same; and means for periodically moving said member outwardly beyond said rotary knife into engagement with a cut sheet, to permit the said rotary knife to clear said sheet.

In testimony whereof I have hereunto set my hand in presence of two subscribing witnesses.

FREDERICK WILLIAM VICKERY.
